UNITED STATES PATENT OFFICE.

CHARLES F. KETTERING, OF DAYTON, OHIO, ASSIGNOR TO THE DAYTON ENGINEERING LABORATORIES CO., A CORPORATION OF OHIO.

ENGINE-STARTING DEVICE.

1,240,348.

Specification of Letters Patent. Patented Sept. 18, 1917.

Application filed September 19, 1912. Serial No. 721,237.

To all whom it may concern:

Be it known that I, CHARLES F. KETTERING, a citizen of the United States, residing at Dayton, county of Montgomery, and State 5 of Ohio, have invented certain new and useful Improvements in Engine-Starting Devices, of which the following is a full, clear, and exact description.

This invention relates to electric starting devices for engines. In devices of this character, the engine is cranked by the operation of the electric starting device, which in this case is a dynamo-electric machine; and after the engine has become self-actuating, it in 10 turn drives the dynamo electric machine to store power in an accumulator or battery. That is, the electric machine first acts as a motor for engine cranking purposes, and then is driven as a generator for battery 15 charging purposes.

It is among the general objects of the present improvements to secure greater efficiency and simplicity for devices of this character.

20 More specifically, these objects are as follows:

To provide a dynamo-electric-machine, capable of furnishing sufficient turning power or torque, which when applied to the 25 crank shaft of the engine, will readily rotate the same and thus start the engine, this power being derived from the accumulator, and conveyed to the dynamo-electric-machine, operating as a motor, in any suitable 30 manner; and at the same time to make the system adaptable so that the dynamo-electric-machine, when the engine has once been started, will operate as a generator and supply current at such a predetermined voltage 35 and amperage, that it will be suitable for use in re-charging the accumulator, or for use in the electric lighting or other work 40 circuits.

In carrying out the above objects of the 45 present invention, there is provided a dynamo-electric-machine, which comprises a plurality of normally independent windings. One of these windings constitutes what may be termed, the motor winding, and is of low 50 electrical resistance, and consists of but a few turns; while the other winding, which may be termed the generator winding, is of much higher electrical resistance and consists of a far greater number of turns.

Each of these windings is connected to 55 independent commutators, said commutators having selective connection with an accumulator; that is, a comparatively low resistance conductor capable of carrying high current values is provided between the accumulator 60 and the dynamo-electric-machine, and is provided with a suitable switch arrangement, whereby, either the motor winding or the generator winding may be connected to the 65 accumulator.

A single set of pole pieces is arranged in the dynamo-electric-machine and carries the 70 motor and generator field windings of the machine, so that it will be seen that the motor and generator armature windings will 75 operate in what may be termed, a common magnetic field.

The voltage relation between the motor and generator windings of the armature, is so proportioned that an accumulator of relatively small voltage and consequently, of a 80 small number of cells, may be employed, which under certain conditions, may be charged and discharged in series.

By being able to charge and discharge the 85 accumulator in series, and by having the aforementioned selective switch arrangement for connecting either the generator side of the machine to the battery, for charging purposes, or connecting the motor side 90 of the machine with the battery, for starting purposes, the mechanical and electrical connections are materially reduced and simplified, as compared with systems of a similar character, heretofore produced.

Another object of the present invention resides in combining the independent motor and generator windings and their accumulator connections, with what may be termed a multiplied or variable connection between 95 the dynamo-electric-machine and the engine, to which the system is applied.

Another object is to make use of the set 100 of generator armature windings to operate the dynamo electric machine momentarily or initially as a motor with a slow initial movement, for the purpose of facilitating the enmeshment of the coupling gears that connect the electric machine to the engine.

Further objects and advantages of the 105 present invention will be apparent from the following description, reference being had to the accompanying drawings, wherein a

preferred form of one embodiment of my invention is clearly set forth.

In the drawings:

Figure 1 is a top plan view of a portion 6 of the chassis of an automobile, to which my improved system is applied. Certain parts of the chassis and automobile are removed for the sake of clearness; the parts of my system which are shown therein, being the 10 particular arrangement and location of the dynamo-electric-machine and connections for controlling the operation of the same.

Fig. 2 is a detail fragmentary view of the differential gear connections between the 15 dynamo-electric-machine and the engine.

Fig. 3 is a vertical sectional view, taken on the line 3—3 of Fig. 5, of the automatic switch.

Fig. 4 is a side elevation of the switch 20 element, the outer casing thereof being broken away to show certain of the co-operating elements.

Fig. 5 is a longitudinal sectional view taken on the line 5—5 of Fig. 3, a portion 25 of the casing which includes the differential connections between the engine and dynamo-electric-machine, also being shown in this view.

Fig. 6 is a plan view of the switch, with 30 the cover removed, clearly illustrating the relation and construction of the electrical contact elements thereof.

Fig. 7 is a detail plan view of the stationary contacts of the switch.

Fig. 8 shows the switch and gear controlling mechanism, latched to the operating 35 elements.

Fig. 9 is a top plan view of the mechanical means for controlling the system.

Fig. 10 is a side elevation of the same, a portion 40 thereof being shown in section for the sake of clearness, with the latching mechanism and operating elements in unlatched position.

Fig. 11 is a diagrammatic view of the 45 electrical circuits and connections embodied in the present invention.

Fig. 12 is a detail diagrammatic view of one form of the dynamo-electric-machine 50 and its co-operating parts and connections.

Fig. 13 is a detail diagrammatic view of a modified form of the system and structure shown in Fig. 12.

Referring to the drawings, and more particularly to Fig. 1, it may be stated that the type of automobile to which this improved system is shown as applied, is known to the trade, as the Cadillac, and embodies an engine of the four cycle type, and in the 60 present instance, is shown as having four cylinders.

In Fig. 1, the side frames of the chassis are designated by the numeral 20, which together with certain transverse supporting 65 members, carry and support the engine 21.

22 and 23 indicate the running boards. 24 designates a portion of the ordinary casing, containing the transmission gears, and 25 is the transmission lever, which, when moved back and forth, controls the selection 70 of the transmission gears in a well known manner, whereby various speeds, forward or the reverse speed may be selected as desired. 26 represents an oil pump, such as is customarily used in a car of this type. 75 This oil pump is operated by the shaft 27, which is ordinarily employed to operate the magneto and which, because of its location, is advantageously made use of in the present system, as will appear hereinafter. 80

28 designates the engine fly-wheel, secured in the usual manner to the engine shaft, and having a series of gear teeth, formed on or secured to its periphery, as at 29.

The transmission clutch 30, is of the usual construction and is adapted to be moved into and out of engagement with the conical surface of the interior of the fly wheel. The movement of this clutch is controlled through the medium of the ordinary clutch 90 spring 31, and by the yoke member 31, by movement of the transverse shaft 32, which may be termed the clutch shaft, and the operation or movement of the ordinary clutch pedal 33, whereby the engine will be 95 connected to and disconnected from the running gear of the vehicle, in the well known manner.

The dynamo-electric-machine 34 is constructed and arranged to serve as a motor 100 for starting the engine, and as a generator for charging the accumulator or storage batteries. This dynamo-electric-machine is controlled, as to its status as a motor or generator, by the clutch pedal or operating 105 member 33.

The means by which the clutch pedal controls the status of the dynamo-electric-machine, will now be described.

Adjacent to one end of the clutch shaft 32, 110 a bracket 35 is loosely mounted thereon; that is, this bracket normally permits relative oscillatory movement of the clutch shaft 32, but is held in fixed position, relative to any transverse or lateral movement thereon. 115

Referring to Figs. 8, 9, and 10, it will be seen that the bracket 35 is provided with an arm 36, which supports the rod 37. This rod, in turn, supports the magnetic coil 38, and constitutes not only a supporting means 120 for the said coil, but also acts as a magnetic core therefor.

The bracket 35 is also provided with a rearwardly extending arm 39, to the outer end of which the armature or latch 40, is 125 pivotally secured as at 41. One end of the armature 40 is normally positioned in alignment with, but spaced from the core of the magnet 38, (see Fig. 10).

The opposite end of the armature 40, is 130

formed in the shape of a hook or latch, as at 42, and is adapted to engage, when the armature is moved into the position shown in Fig. 8, with the curved arm 43, which in turn, is rigidly secured to the clutch shaft 32, by any suitable means.

The formation of the engaging end of the arm 43 and the armature 40, is so arranged that these two elements may be maintained in latched position by a slight pressure being exerted on the clutch pedal, after the two elements have initially been brought into latched position.

In order to limit the movement of the armature 40, when returning to its open position, and also to adjust the distance through which it is necessary for the armature to travel, in order to be in such position that it will engage with the arm 43, when said arm is moved, there is provided a combined adjusting and stop mechanism, in the shape of a screw bolt 66, which passes through a threaded bore in the lug 40^a, formed on the armature 40.

This bolt is adapted to project through said lug, and contact with a projection 67, secured to the arm 39, so that it will be seen by adjusting the bolt 66, the armature 40 will be moved so as to increase or decrease the distance between the core of the magnetic coil and the end of the armature.

A spring 68, one end of which is secured to the armature 40, and the other end to the pin 69, carried by the arm 39, constantly tends to hold the armature in its normally unlatched position.

By referring to Figs. 8 and 10, it will be seen that the engaging end of the arm 43, when in its unlatched position, will rest against a beveled face 41^a, formed on the armature 40. This structure permits a camming action of the arm 43, relative to the armature 40, when the clutch pedal is moved to its normal home position, thus positively forcing the armature into an unlatched position.

A construction, embodying certain of the above described elements, has been fully set forth in my Patent 1,150,523, dated August 17, 1915.

On the same pin which acts as a pivot point for the armature 40, there is secured a rod 44, provided with a shoulder 45, against which one end of the coil spring 46 abuts.

The other end of the rod 44 passes through an opening, formed in the plate 47, which may be secured to the frame of the chassis or to any suitable part of the machine, as at 48.

It will, of course, be understood that this plate 47 not only acts as a guide for the rod 44, but also forms the opposite or stationary abutment for the spring 46.

The function of this structure just described, will be fully explained in connec-

tion with the operation of the clutch pedal, when actuated to control the starting mechanism.

The bracket 35, which is normally loosely mounted on the clutch shaft, has permanent connection with the gear and switch shifting mechanism, by having the arm 36 connected at its lower extremity, with the yoked rod 49, which in turn is provided with a shoulder 50, forming an abutment for the spring 57. This rod 49 has an internal bore, as at 51, to receive the screw threaded end of the connecting pin 52, the opposite end of which passes through the bearing block or collar 53, and is secured to the yoked arm 54, by means of the gib 55. The connecting pin 52 is provided with an elongated slot 56, through which the gib 55 passes, so that it is possible to move the pin 52, and the elements having positive connection therewith, relative to the securing means 55, and the arm 54.

The bearing block 53 is provided with a shoulder, oppositely disposed, relative to the shoulder 50, and forms an opposite abutment for the spring 57.

The yoke member 54 is adjustably connected by means of a screw threaded connection, with the shaft 58, which is connected directly to the differential gearing 60, by means of the yoke member 59.

This gearing 60 constitutes the movable elements of the differential connections between the dynamo-electric-machine and the engine, and comprises a pair of gear wheels 61 and 62, which are of substantially the same construction as those shown and described in my above mentioned patent and also my Patent No. 1,171,055, dated February 8, 1916, and therefore, no further description of the specific construction of the gearing and its self contained clutch mechanism, will be given.

It is, of course, understood that as soon as the engine becomes self-actuating, the gearing 60 should be released, by simply releasing the clutch pedal, but if, for any reason, this gearing is improperly maintained in enmeshed condition, the roller clutch mechanism, self contained within the gearing 60, as is clearly shown in Fig. 2, will permit the engine to run free of the dynamo-electric-machine.

When the dynamo-electric-machine and the engine have been brought to rest, the gear wheels 60 may be in such a position, relative to the gear teeth of the fly-wheel and the motor pinion 63, that the end faces of the respective enmeshing gears, will be in direct alinement so that upon attempting to shift the gearing, the end faces thereof, will come in contact.

In order to obviate this objection, and also to facilitate and make more certain, the proper engagement of the gearing 60, with the motor pinion and the fly-wheel, it has

been found advisable to transmit current to the dynamo-electric-machine, to operate the same as a motor, at a slow initial speed, as a preliminary movement to its normal starting operation. One way of securing this slow initial movement is described in the above mentioned Patent No. 1,150,523.

It is also provided, as will be seen by referring to Fig. 1, that there is a greater side clearance between the gear wheel 61 and the fly-wheel gearing, than there is between the gear wheel 62 and the motor pinion 63, of the armature. This, of course, results in the meshing of the gear wheel 62 and the pinion 63, previous to the engagement of the fly-wheel gear teeth, by the gear wheel 61.

It will now be seen that if the dynamo-electric-machine is given a slow preliminary movement, as a motor, and the means for shifting the gearing 60, is operated, the gear wheel 62 will immediately be picked up by the pinion 63, and the gearing 60 rotated in such a manner that the gear wheel 61 will readily be brought into enmeshment with the gear teeth of the fly-wheel.

The circuit connections for giving this slow preliminary movement to the dynamo-electric-machine, acting as a motor, also permit the carrying out and accomplishment of a various number of novel functions.

If the engine 21, (see Fig. 1), is at rest, it will be obvious that the coupling or multiplied gearing 60, will be in non-driving position.

Now, if it is desired to start the engine, the initial operation consists of depressing the push button 210, (see Fig. 11), which results in the closing of the supplemental or starting circuit, which will be more fully described hereinafter, in connection with detail description of the diagrammatic figures.

By referring to Fig. 11, it will be seen that this supplemental or starting circuit includes the coil 38, and then directly connects to the leads or connections of the generator winding, in such a manner that it short-circuits the cut-out 230 which is described hereinafter.

The current passing through this independent or supplemental circuit, will, of course, energize the magnetic coil 38, whereby the contact end of the pivoted armature or latch 40, will be attracted and so moved that the latch end 42 thereof, will lie in such position that immediately upon the shifting of the clutch pedal, it will engage with the end of the arm 43.

In the present instance, it has already been explained that the leads, connecting the motor winding and the accumulator, and those connecting the generator and accumulator, are of different electrical conductivity, that is, these connections are of different resistance, the connection between the motor winding and the accumulator being of greater

conductivity and also of lower resistance than the connections between the generator winding and the accumulator. The above named connections, however, are each adapted to be connected to an accumulator of a substantially constant voltage, that is, this accumulator or battery has a given number of cells connected in series at all times.

In order to operate the dynamo-electric-machine, as a motor, at a slow initial speed, I utilize the relatively high resistance generator winding, rather than to use the ordinary motor or series winding, through which the current is passed to effect the starting operation.

Now, as soon as the supplemental circuit has been closed (by depressing button 210), this circuit energizes the latch magnet 38 to couple the clutch pedal to the gear and switch operating mechanism shown in Figs. 9 and 10. Thus it will be seen that pressure exerted upon the clutch pedal, to move the same in a forward direction, will not only accomplish the usual function of disengaging the engine from the transmission clutch, but will also result in the oscillatory action of the entire bracket 35, together with a rearward shifting of the lever connections and consequently the like shifting of the gearing 60.

By using the clutch pedal to effect the shifting of the gearing 60, it will be seen that the engine will be free from any heavy load, such as its connection with the running gear of the vehicle, at the time of the starting operation, thus tending to eliminate any danger of stalling the engine, by attempting to start the same when an extreme load is imposed thereon, as might be the case, if the transmission lever 25 was inadvertently maintained in an improper position.

Now, as soon as the clutch pedal 33 has been operated, it will be seen that the rod 44 will be forced through the plate 47, thus compressing the spring 46. It will also be apparent that the oscillatory action of the bracket 35, to which the rod 44 is attached, will effect such movement thereof, that the pivot point 41, will be moved slightly beyond center.

This is important, for as soon as the clutch pedal is released, and starts to return to its normal position, under the effect of the ordinary clutch spring, the spring 46 will, previous to return of the pivot point 41, of the rod 44, below center, exert a holding effect, relative to the bracket, and the elements carried thereby, so that the movement of the clutch shaft will instantly cause the arm 43 to disengage from latched position with the armature 40.

That is, as the clutch pedal 33 is pressed forward, the magnet 38, together with the bracket 35, will be swung in the direction shown by the arrow in Fig. 10. This will,

5 of course, compress the spring 46 against the plate 47, in such a manner that when the pedal 33 is released by the operator, the spring 46 will force the magnet and its bracket back into the position shown in Fig. 10, which will, of course, bring the pivot point 41 into its correct and normal position.

10 Of course, it will be understood that the operator releases the pressure on the push button 210, as soon as the above described latching to the clutch pedal has occurred. This restoring of the push button 210 to normal undepressed position breaks the 15 supplemental circuit, and by the deenergizing of the magnet 38, the latch armature 40 is released from engagement with the arm 43. Then the spring 68 will effect the return of the armature to its normally unlatched position.

20 When the rod 44 is moved so that its pivot point is below center, the effect of the compressed spring will be exerted to cause a snap action return movement of the bracket 25 35 and the elements connected therewith, to their normal home position.

It will now be seen that inasmuch as the 30 armature is being maintained in its unlatched position, through the effect of the spring 68, it will be possible to operate the clutch pedal 33, to couple and uncouple the coöperating elements of the engine clutch, in the usual manner, without, in any way, effecting the mechanism employed during 35 the starting operation.

The springs 46 and 57 must be so proportioned that they will equalize to a certain extent, relative to each other and also relative to the clutch spring which normally 40 forces and maintains the clutch in engaged position with the engine fly-wheel, in the usual manner.

It will therefore be seen that this clutch 45 spring maintains the clutch pedal in its normal position, and therefore, when the clutch pedal has been connected up, so as to shift the gear and switch connections, as described heretofore, it will have to be operated against the pressure of the clutch 50 spring, in the usual manner, so that as soon as the operator relieves pressure from the clutch pedal, this spring will not only immediately tend to bring the co-öperating elements of the clutch into engagement, but 55 will also effect the shifting of the gear and switch connections, from their starting to their charging position.

It is well known that in the manufacturing and assembling of large quantities of 60 motor vehicles, there will be a variance in the movement and the normal home position of the clutch pedals of the various vehicles.

It is also well known that after vehicles 65 have been in use for some time, the coöperat-

ing elements of the clutch mechanism will tend to wear. This is especially true in constructions where the cone type clutch is used, as is present in vehicles of the Cadillac type.

70 When this wear occurs, it will, of course, be obvious that the home position of the clutch pedal is altered, inasmuch as the movable element of the clutch must be moved in farther, in order to have the 75 proper engagement with its coöperating clutch element.

Now, in the present system, where the clutch pedal constitutes the controlling element of the starting system, under certain 80 conditions, the normal home position of the clutch constitutes an important point, inasmuch as the arm 43, which is carried by the clutch shaft, will also be thrown out of its normal home position, in the same manner as the clutch pedal is.

This arm 43, which has been described as having an enlarged head for engaging the latch end of the armature 42, normally rests on a portion of the armature, and consequently would tend to move the entire bracket 35 and the mechanism connected thereto and supported thereby, out of its normal position.

However, when the bracket 35, and the 95 magnetic clutch, supported thereby, are in their normal position, the connecting elements between the bracket 35 and the gearing 60, have forced the gearing out of coupling position, and into such position that 100 one of the faces of the gear wheel 62, will be in abutment with the adjacent face of the end casing of the electric machine.

For the above reasons, it is advisable to 105 provide a plurality of adjustments for the connections between the gearing 60 and the bracket 35.

For instance, when the system is assembled and applied to the vehicle, the rods 58 and 54 are so adjusted, relative to each other, 110 by means of the screw threaded connection at 58°, that the clutch pedal, in its normally home position, will have absolutely no effect on these connections, that is, the arm 43, which is rigidly connected with the clutch 115 shaft, will not exert any pressure on the armature 40.

It will, therefore, be seen that the initial 120 adjustment will be effected by properly positioning the rod 58, relative to the yoke member 54.

By referring to Fig. 10, the various elements are clearly shown in their correct position, when the system, so far as the clutch 125 pedal is effective relative to the starting mechanism, is in inoperative position.

However, in case of wear between the coöperating elements of the clutch, and the tendency of the clutch pedal to swing farther back from its normal position and thus 130

cause the shifting of the bracket 35 and its coöperating elements, it will be seen that this may be compensated for by means of the resilient connection which is interposed between the rod 49 and the yoke member 54.

This connection has been described in detail heretofore, and is made possible by providing the connecting pin 52, with an elongated slot, through which the gib 53 passes, so as to permit movement between the pin 52 and the elements positively connected thereto, relative to the yoke arm 54, and consequently the gear 60.

By providing this resilient adjustment, it will be seen that the clutch spring will only be required to overcome the effect of the spring 57, in order to maintain the clutch elements in their proper engaged position.

As has been stated heretofore, one of the objects of the present invention is to provide a dynamo-electric-machine, with independent windings and connections, so arranged and constructed that an accumulator may be employed, with constant series connection, that is, as differentiated from the type of systems, wherein it is necessary to employ a battery, having series and parallel connections.

These independent windings, in the present instance, vary in their amperage relation. That is, in order to secure sufficient torque to operate the electric machine, as a motor, to effect the cranking or turning over of the engine, I have devised an arrangement for utilizing such windings as will constitute a series motor, adapted to operate under relatively high amperage.

These motor windings, as previously referred to, are of less resistance and few turns. That is, the armature of the dynamo-electric machine is provided with this set of low resistance armature windings which for convenience may be termed the motor windings, and which are utilized for the cranking operation.

But then, in order to secure proper generating conditions, I make use of an entirely different set of armature windings (wound on the same armature of the dynamo-electric machine), for the generating function.

The generator armature windings are of high resistance and greater number of turns, as compared to the motor armature windings.

This arrangement enables the apparatus to be so designed as to give high torque or cranking power for starting the engine, and at the same time results in the proper generating function.

This, therefore, is the reason for having the generator windings and the motor windings of different current conductivity.

By including the armature windings, for both the motor and generator types of machine, on a single armature core, as is clearly shown in Figs. 12 and 13, it is also possible to employ but a single set of pole pieces, in-

asmuch as each of these windings can operate to accomplish their own functions, in a common magnetic field, it simply being necessary for the armature windings, which are employed when the machine is operating as a motor, to be connected to an independent commutator, insulated from the commutator to which the windings, which are employed, when the machine is being used as a generator, are secured.

Because of the fact that there are two separate and independent sets of windings employed for effecting the operation of the machine, as a motor, and as a generator, some means must be provided for shifting the connections between the respective windings of the dynamo-electric-machine and the accumulator, so that the electrical connection of the accumulator with the relatively low conductivity generator leads, may be broken, and connection established with the high conductivity leads, for transforming the machine into a motor, for starting purposes, and for reversing this action, that is, breaking the motor circuit and establishing the generator circuit, when the engine has become self-operating and the dynamo-electric-machine is being operated as a generator.

It will be advantageous to effect this shifting of connections between the motor and generator circuits and the accumulator, by the same operation which causes the shifting of the gears 60, to connect up the dynamo-electric-machine, as a motor, with the flywheel of the engine.

However, it should be understood that it is advisable to provide some means for delaying the establishing of connection between the motor circuit and the accumulator, until after the gearing 60 has been brought into its coupling position with the dynamo-electric-machine and the engine.

The means for shifting the accumulator connections with the respective circuits of the electric machine and the means for delaying the operation of the above means, until after the enmeshment of the gears, will now be fully described.

Referring to Figs. 4 and 5, the numeral 81 designates a sleeve, mounted upon the rod 58, and having a projecting finger 82, which in turn is connected with the shaft or rod 83, which may be termed the controller switch rod. The structure of the switch, which is clearly shown in Figs. 3, 4, 5, 6, 7, and 8, comprises a casing 84, through which passes the shaft 83. The casing 84 is formed integral with the end housing 85 of the dynamo-electric-machine, which incloses and contains the gear 60. Within the casing 84, there is a coil spring 86, mounted upon the shaft 83, said spring having as one abutment, the cap 87, and as its other, the block 88. This block is slidably mounted on the rod 83, and is held in normal position by means

of the spring 86, against the latch yoke 89, said yoke being pivoted to the opposite sides of the casing 84, as is shown in Fig. 6. The yoke 89 is provided with a pair of fingers 90, which extend along each side of the block 88, and normally are in engagement with the rollers or pins 91, which, in turn, are fastened to or carried by the block 88, and which are adapted to travel on the tracks 84^a, which are formed by providing flanges on the interior of the casing 84. See Fig. 3.

This latch yoke 89 is maintained in normal position by means of the spring 94, fitted within a bore 95, formed in the casing 84, said spring having a cap or cover 96, which is in direct contact with the rear end of the latch yoke 89.

The block 88 forms a base or support for the contact element 98, which is provided with a pair of parallel grooves 101 and 102, engaging respectively with the common contact bar 103 and the aligned, but insulated, bars 104 and 105, respectively.

In order to compensate for any inaccuracy of the switch elements and to make more certain the contact therebetween, the plate 98 is resiliently mounted with respect to the bars 103, 104 and 105. This is effected by passing a pair of screws 106, down through insulating bushings, located in the plate 98, into the threaded bores, formed in the block 88. The block 88, adjacent to each of the threaded bores, is counterbored, as at 107, to receive the coil springs 108, which normally force the plate 98, up into contact with the bars 103, 104 and 105, but permit a certain amount of relative movement between said elements and at the same time, maintain a good electrical contact therewith.

It is advisable that the movable contact element 98 be shifted from its normal position to the starting position, with a quick snappy movement, so as to prevent arcing and also to have the shifting effect take place at a given time, relative to the movement of the gearing 60.

In the present instance, it will be seen that so long as the arms 90, of the yoke 89, tend to hold or engage with the rollers 91, carried by the block 88, it will be impossible to cause a shifting of the electrical connections between the various windings of the electric machine and the accumulator, and it will further be seen that until the yoke member 89 is raised, so that the arms 90 will disengage the lugs or rollers 91, the block 88 and its contact plate 98, will be maintained in the position shown in Fig. 5, regardless of the position of the rod 83 and its co-operating elements.

However, in order to disengage the yoke member 89, at a certain predetermined point, there is a trip arm 107^a, pinned fast to the rod 83, so that when the clutch pedal is ac-

tuated to shift the gearing 60, it also automatically shifts the rod 83, and the trip block or arm 107^a, without affecting the position of the contact block 98, relative to the contact bars or rods 103, 104 and 105, and at the same time, will cause the spring 86 to become highly compressed between the cap 87 and the face of the block 88, against which it normally abuts.

Now, it is arranged that as soon as the gearing 60 has become enmeshed with the proper gear wheels, the trip arm 107^a will be brought into such position that it will strike the face 108^a of the yoke 89, and will immediately trip the same, and thus throw the arms thereof, out of engagement with the rolls, carried by the block 88.

As soon as the arms 90 have been released from engagement with these lugs, the spring 86 will immediately tend to expand, and will, of course, force the block 88 and contact plate 98, rearwardly, so as to cut out one set of connections between the windings of the electric machine and accumulator, and establish connections between a different set of windings and the accumulator. The switch is returned to normal position shown in Fig. 5, whenever the clutch pedal is released, whereupon the movement of the rods 58 and 83 (to the left in Figs. 4 and 5) causes the block or arm 107^a, which is fast to the rod 83, to abut against the movable switch block 88 and restore the switch to its normal position, making the generating circuit.

Certain of the windings and combinations thereof, are shown in the following views, as for instance;

In Fig. 4, there is clearly shown a view, wherein the switch is in starting position, that is, in position so that the motor winding of the dynamo-electric-machine is connected directly with the accumulator, while in Fig. 5, the contact plate is shown in charging position, whereby the generator windings are connected with the accumulator and the connections between the motor winding and the accumulator are broken.

By referring to the diagrammatic views, and more especially to Figs. 12 and 13, it will be seen that the system embodies an armature, carrying a plurality of windings, operable in a field composed of a single set of pole pieces.

Fig. 12 clearly shows the connections of the armature and the field windings, so constructed and arranged that the armature is provided with a plurality of commutators on one end of its shaft. These commutators are independent of, and insulated from each other, and have absolutely separate and distinct connections with the motor and generator windings of the system.

In Fig. 13, there is shown a modified form of the electric machine construction, where-

in one end of the armature is provided with a commutator, connected to the generator winding, while the other end thereof, carries the commutator for the motor winding.

In describing the electrical connections and circuits shown in diagrammatic Fig. 11, the circuit connections, as they appear when the machine is at rest, and the system is to be used for starting, will be first described.

By referring to Fig. 11, it will be recognized that the current stored up in the accumulator 100, will always tend to flow back through the generator side of the machine, because of the fact that the controller switch has no neutral position, but normally rests in the position to close the charging or generator circuit.

However, as has been clearly set forth in my co-pending applications, filed June 15, 1911, Serial No. 633,443, and filed April 17, 1911, Serial No. 621,512, I have included within this circuit, a current interrupter, or cut-out relay 230, the function of which is to prevent the back flow of current from the accumulator into the generator, at such times as the generator is at rest, or at such times as the generator may be operating, but the voltage of its out-put is less than the voltage of the storage battery.

Inasmuch as it is advisable to give the dynamo-electric-machine a slow initial movement, as a motor, previous to the operation of the electric machine, to start the engine, I have provided a circuit which simply shunts out or short-circuits the cut-out device, so that when the supplemental circuit is closed, the current from the accumulator will flow back through the generator winding of the machine, and operate it as a motor, at 6 volts, but simply with the amount of current which the generator leads are capable of carrying.

As has been explained heretofore, the latch magnet is included within this supplemental circuit above named, so that, concurrently with the operation of the dynamo-electric-machine, as a motor, at a slow initial speed, the clutch magnet will be energized that its armature will be attracted so as to lock the operating mechanism and the shifting mechanism securely together.

By referring to Fig. 11, the circuit for accomplishing the preliminary movement of the dynamo-electric-machine, will first be described.

From the accumulator 100, the current will flow through the short wire 200, thence into the wire 300, which leads to the common contact, plate 103, of the controller switch heretofore described.

As has been explained heretofore, the movable element of the switch, is normally in position to close the generator circuit, as is clearly shown in full lines in Fig. 11.

The current will therefore flow from the contact bar 103, through the plate 98, into the co-operating bar 104, thence through the brush 202, of the generator through generator armature winding to the opposite brush 204, wire 205, magnetic coil 38, wire 206, contact plates 207 and 208, which must be closed by the actuation of the push button 210, wires 211, 212 and 213, back to the battery.

The field circuit, when the machine is operating as a motor at a slow initial speed, that is, by passing current from the battery, through the generator windings, will be as follows,—from the wire 300, a portion of the current will branch through the wire 240, thence through the elements 241 and 266 of the regulator, wire 242, across the field winding 243 to the brush 204. It will be understood that the wire 240 is, in substance, connected up to the brush 202. It will thus be seen that the machine will be operating as a shunt wound motor, and inasmuch as it is one of the characteristics of a shunt wound motor to operate at a relatively low torque, the desired effect will be secured. That is, the function of imparting an initial movement to the electric machine is primarily to facilitate the coupling up of the shiftable gearing between the electric machine and the engine, but this initial movement of the armature is not intended to have the effect of operating the motor for starting purposes.

Now, as soon as the current has caused the operation of the dynamo-electric-machine, as a motor, at a slow initial speed, and the gear mechanism between the motor end of the electric machine and the engine has been connected up, the controller switch is operated in a manner heretofore described, so that the contact plate 98 will be shifted from the full line position, to the dotted line position, as is shown in Fig. 11. This will, of course, break the circuit connection between the generator 203 and the battery; and will connect the motor 310 directly with the accumulator, through the following circuit.

From the accumulator 100, through heavy wires 200 and 300, common contact bar 103, plate 98, to the bar 105, through the series field 220, through the brush 204*, across the armature winding 310, through brush 205*, and back to the battery, via the wires 221, 222 and 213.

With these connections, the current will flow directly through the motor winding of the electric machine, from the accumulator at a certain given voltage, and at a sufficient amperage to operate the electric machine as a motor, with sufficient torque to readily turn the engine shaft, through the medium of the gearing heretofore described.

As soon as the engine has become self ac-

tuating, the operator of the vehicle will release the clutch pedal to permit the same to return to its normal position, which as has been explained heretofore, will cause the

5 contact element 98, of the controller switch, to be shifted from the position shown in dotted lines to the position shown in full lines in Fig. 11, thereby breaking the connection of the motor circuit.

10 By referring to my co-pending application, filed June 15, 1911, Serial No. 633,443, there is clearly shown a suitable clutch mechanism embodied in the front end of the generator, which is of such structure 15 that it will readily permit the operation of the electric machine as a motor, for cranking purposes, independently of the rod 27, which, of course, will be operated through the gearing 105, as soon as the engine is 20 operated by the motor.

A further clutch mechanism, such as is shown in Fig. 2, has also been clearly described in the above referred to application; this clutch mechanism being adapted to permit the running ahead of the engine, relative to the armature of the motor. This condition might occur in the event that the operator inadvertently permits the shiftable gearing to remain in position to couple up 25 the electric machine and the engine, after the engine has started to operate on its own power.

Now, as soon as the engine becomes self-operating, and the engine drives the shaft 30 27 at a speed equal to or greater than the armature speed, the front end clutch will become effective to drive the electric machine as a generator.

The generator or front end clutch may be 40 suitably inclosed in the casing 70, and in view of the description and illustration of this structure in the application heretofore referred to, it is not thought necessary to illustrate and describe in detail this clutch mechanism in the present application.

Further description of the means and connections for driving the electric machine, as a generator, will not be given in the present application.

50 Now, as soon as the speed of the engine drives the dynamo-electric-machine, as a generator at a certain predetermined speed, the current generated by the machine, will initially flow through the shunt circuit of the generator, that is, through the brush 202, contact plates 104, 98 and 103, respectively, wire 300, branch wire 240, through the regulator 241, which will be described herein-after, wire 242, through the winding 243 55 and back across the generator, via the brush 204.

At the same time, a small amount of current will tend to build up the cut-out relay or current interrupting device, by passing through the brush 202, contact plates

104, 98 and 103 respectively, wire, 300, high resistance wire 244, high resistance winding 245, wire 246, back to the brush 204 of the generator.

It will be understood that when the current has built up through the fine wire coil 245, of the cut-out relay device, to energize the core 249, sufficiently to attract the armature 250, and thus close contact with the plate 251, the flow of current will change 76 and progress through the course of least resistance, namely, from the wire 300, through wire 200, across the battery 100, through wire 213, branch wire 212, through the contact 251, and armature 250, heavy 80 winding 255, branch wire 260, thence into wire 246, back to the generator brush 204.

One of the characteristics of a shunt wound generator is that the initial flow of current tends to build up through the shunt or exciting field, while at the same time, a certain proportion of the current flows through the main circuit connections.

Inasmuch as the present system embodied a battery which is preferably to be charged 90 at a certain predetermined voltage, some means must be provided for preventing the voltage across the main lines of the circuit, from increasing beyond this point.

In the present instance, there is provided 95 a regulator which may be of substantially the same construction as that shown and described in my co-pending applications, filed August 9, 1912, Serial No. 714,234, and filed November 11, 1912, Serial No. 730,733.

As will be seen by referring to Fig. 11, this regulator comprises a casing 241^a, wherein a suitable conducting liquid is placed, and which normally covers the resistance winding 266, which is placed in 105 series in the shunt field, and is carried by the plunger element 265, which also projects downwardly into the mercury cup or casing 241^a.

The plunger element 265 is controlled by 110 means of current which passes through a circuit connection placed directly across the lines of the generator, so that a small portion of the current which tends to pass from the generator to the battery 100, will be 115 shunted through the controlling or voltage winding 267.

This winding 267 and the plunger 265 are so arranged that when the voltage of the coil 120 267 rises above a certain predetermined point, the plunger element 265 will be drawn upwardly, consequently withdrawing some of the turns of the resistance winding 266, from the mercury contained in casing 241^a, and cutting the same into the shunt circuit.

Now, as soon as the resistance is cut into the shunt circuit or field, the strength of the said field will be reduced and therefore the voltage of the current flowing through the 125 130

generator and battery connections, will also be reduced, so as to bring the output of the machine to the proper voltage.

As has been fully explained in my co-pending applications, filed Aug. 9, 1912, Serial No. 714,234, and filed November 11, 1912, Serial No. 730,733, I have included a rheostat in series with the winding 267, for the purposes clearly set forth in my co-pending applications.

Supposing that the generator is operating at such a speed that the voltage has been brought up to a point to close the cut-out relay, and is increasing beyond the proper point for charging the battery 100, or for furnishing current to the lighting circuit, which comprises the leads 275 and 276, and the ignition circuit which comprises the leads 285 and 286. It will be seen that the current will flow through the brush 202, contact plates 104, 98 and 103, the common wire connection 300, wire 200, battery 100, wire 213, branch wire 212, contact 251, armature 250, heavy winding 255, through the wire 260, back to the generator, through the wire 246, and brush 204.

There will also be a flow of current at the same voltage as the circuit just described, from the wire 300, through the wire 240, through the voltage coil 267, through the rheostat 290, to the line wire 246 and thence back to the generator.

This last circuit constitutes the controlling circuit above referred to.

The rheostat 290 is arranged in series with the controlling coil 267, in such a manner that the determined voltage for controlling the plunger element of the regulator may be kept substantially constant, irrespective of the effects of temperature changes, etc., on the voltage coil, by simply cutting in or out more or less resistance, as conditions may demand.

Now, as the voltage in the line wire 300 increases, the voltage of the current passing through the coil 267, will correspondingly increase and at a certain predetermined point, will so effect the plunger 265, as to withdraw the same from the mercury cup 241^a, thus cutting in resistance into the shunt field, so that the flow of current through the shunt or exciting field, will be as follows:

From the brush 202, through the contact plates 104, 98 and 103 respectively, wire 300, wire 240, into the mercury contained in the cup 241^a, and through whatever turns of the resistance winding 263, which may be withdrawn from the mercury, thence through the wire 242, back to the generator.

By arranging the lighting circuit and the ignition circuit in the form shown in Fig. 11, it is possible to take current, either directly from the generator 203 or from the battery 100, it simply being necessary that

the ignition system comprise a complete wire circuit, rather than any ground connections, so that there will be no interference with the lighting circuit, under any conditions.

In Fig. 12, there is shown a single set of pole pieces 300^a, which carry both the generator and motor windings, while the armature which also carries the motor and generator windings operates between the pole pieces 300^a.

The armature windings of both the motor and generator types, are arranged in superposed relation, so that the leads from the generator winding may be brought out into engagement with the various bars of the commutator 301, while the leads from the motor winding are so arranged that they may be brought into contact and secured to the bars of the commutator 302. The commutators 301 and 302, are insulated from each other, as are also the motor and generator windings, so that the operation thereof, will consequently be independent of each other.

In Fig. 13, there is shown a modified form of the structure shown in Fig. 12, inasmuch as the commutator connected with the generator winding, is positioned on the opposite end of the armature shaft, relative to the commutator connecting with the motor winding.

It is extremely important in the present system, that the leads and windings of the motor be of much less resistance and therefore, heavier and of greater electrical conductive capacity, than the leads and windings of the generator, and it is therefore necessary that the brushes 304, of the motor, also be much larger and of greater carrying capacity than the generator brush 305.

Further description of the operation of the present invention, as embodied in the modified form, is not thought to be necessary, inasmuch as the operation of the system will clearly appear from the description heretofore given.

It should be readily apparent to those skilled in the art, that suitable electrical connections and circuits may be arranged to permit the carrying out of the invention, in a various number of manners, other than heretofore described.

While the form of mechanism herein shown and described constitutes a preferred form of embodiment of the invention, it is to be understood that other forms might be adopted, all coming within the scope of the claims which follow.

What I claim is as follows:—

1. In an engine starting system, the combination with an engine, of a starting device therefor including a dynamo electric machine having its armature wound with two independent sets of windings, one set comprising motor armature windings of 130

- relatively low resistance and few turns, and the other set comprising generator armature windings of higher resistance and a greater number of turns than the motor armature windings; connections between the engine and the starting device for starting the former by the latter and running the latter by the former; an accumulator; and means for connecting the motor armature windings to the accumulator to secure high torque effect for starting purposes, and to connect the generator armature windings to the accumulator to secure charging of the accumulator at relatively low current values.
2. In an engine starting system, the combination with an engine, of a starting device therefor, including a dynamo electric machine having a set of motor armature windings of relatively low resistance and few turns, and an independent set of generator armature windings of higher resistance and a greater number of turns than the set of motor armature windings; motor field windings and generator field windings; connections between the engine and the starting device for starting the former by the latter and running the latter by the former; an accumulator; and means operable to connect the motor armature and motor field windings to the accumulator for starting purposes, and to connect the generator armature and field windings to the accumulator for generating or charging purposes.
3. In an engine starting system, the combination with an engine, of a starting device therefor including a dynamo electric machine having a motor armature winding of relatively low resistance and few turns, and an independent generator armature winding of higher resistance and a greater number of turns than the motor winding; a series field winding of relatively low resistance for motor operation, and a shunt field winding for generator operation; connections between the engine and the starting device for starting the former by the latter and running the latter by the former; an accumulator; and means for connecting the motor armature winding and said series field winding to the accumulator to secure higher torque effect for starting purposes and to connect the generator armature winding and shunt field winding to the accumulator to secure charging of the accumulator at relatively low current values when the dynamo electric machine is operated as a generator by the engine.
4. In an engine starting system, the combination with an engine, a starting device therefor, including a dynamo electric machine having independent motor and generator armature windings of relatively low and high resistance respectively, an accumulator adapted to be connected to either of said windings, and differential connecting devices between the electric machine and engine for cranking the engine at one ratio of speed and for driving the electric machine as a generator at a different ratio of speed; and selective means for establishing connection between the motor winding and accumulator, and for connecting the engine and electric machine through certain of the differential connections to crank the engine at one ratio of speed for starting purposes, and to then disconnect these differential connections and break the connections between the accumulator and motor winding when the engine becomes self-actuating, and to establish connections between the generator armature winding and the accumulator, with provisions to connect the electric machine and engine through other differential connections whereby the engine may drive the electric machine as a generator at a different ratio of speed for charging purposes.
5. In an engine starting system, the combination with an engine, of a storage battery, and a dynamo electric machine including an armature, and connections between the battery and the dynamo electric machine and the engine for starting the engine by the dynamo electric machine, and running said electric machine by said engine; of means operating to vary the effective conductivity of the armature to increase said conductivity and operate with high torque when the electric machine operates as a motor with current derived from the battery to start the engine, and to reduce the conductivity of the armature when the electric machine is driven by the engine to act as a generator to charge the storage battery.
6. In an engine starting system, the combination with an engine, of a starting device including a dynamo electric machine adapted to operate as a motor for starting said engine, and to be operated as a generator when the engine becomes self-actuating, said dynamo electric machine having independent sets of armature and field windings of different conductivity; an accumulator having electrical connections adapted to be connected with the respective sets of armature and field windings; differential connecting devices between the engine and electric machine; and selective means operable to connect the set of armature and field windings of greater conductivity to the accumulator, and to connect the engine and electrical machine through certain of said differential connections, when the engine is to be operated as a motor for starting purposes; and when the engine becomes self-actuating to then dis-establish said electrical and differential connections and to connect the armature and field windings of the electric machine of less conductivity to the accumulator through another set of electrical connections, and to connect the engine to the electric ma-

chine through other differential connections when the machine is to be driven as a generator by the engine for charging purposes.

7. In a starting system, the combination with an engine; of a starting device therefor, comprising a dynamo electric machine having a generator armature winding and a motor armature winding; means for mechanically connecting the engine and starting device together; and means for passing current through the generator armature winding to operate the electric machine as a motor, to facilitate the connecting of the starting device to the engine, by said mechanical connections.

8. In an engine starting device, the combination with an engine; of a starting device therefor, comprising a dynamo electric machine having generator armature windings and independent motor armature windings; an accumulator; shiftable mechanical connections for connecting the electric machine to the engine for starting purposes; and means for connecting the generator armature windings with the accumulator to operate the machine as a motor, previous to the shifting of the mechanical connections to connect the machine to the engine for starting purposes.

9. In an engine starting system, the combination with an engine, of a starting device therefor including a dynamo electric machine having motor armature windings of relatively low resistance and few turns and independent generator armature windings of high resistance and a greater number of turns than the motor windings; high ratio and low ratio gearing sets between the engine and the starting device for starting the former by the latter and running the latter by the former; an accumulator; and means for connecting the electric machine with the engine through the high ratio gearing and for connecting the motor armature windings with the accumulator to secure high torque effect for starting purposes, and for connecting the electric machine with the engine through the low ratio gearing and for connecting the generator armature windings of the machine to the accumulator to secure charging of the accumulator at relatively low current values.

10. In an engine starting system, the combination with engine, of a starting device therefor including a dynamo electric machine provided with a plurality of armature windings adapted for selective arrangements as motor and as generator; an accumulator; connections between said electric machine and said accumulator; high and low ratio gearing connections between the starting device and the engine; and devices for controlling said gearing connections and said armature windings first to select an armature winding arrangement having a

higher effective electrical conductivity and contemporaneously establish the high ratio gearing connections for starting, and then to select an armature winding arrangement having a lower conductivity and contemporaneously establish the low ratio gearing connections for charging.

11. In an engine starting and lighting system, in combination with a low voltage lighting circuit, of an engine, a starting device therefor including a dynamo electric machine having a motor armature winding of relatively low resistance and few turns, and an independent generator armature winding of higher resistance and a greater number of turns than the motor armature windings; connections between the engine and the starting device for starting the former by the latter and running the latter by the former; a low voltage accumulator with connections for supplying low voltage current to said lighting circuit; and means for connecting the motor armature windings to the accumulator to receive current of the same voltage as the voltage of the lighting circuit to cause the motor operation of the machine with high torque effect for starting, and to connect the generator winding to the accumulator to secure charging of the accumulator at relatively low current values.

12. In an engine starting system, the combination with an engine, of a storage battery, and a dynamo electric machine with a plurality of armature windings; mechanical connections between the electric machine and engine; electrical connections between the armature windings and the battery; and means for selectively controlling said armature windings and connections to cause said machine to operate either as a high torque motor adapted to crank the engine, or a generator adapted to charge the battery.

13. In an engine starting system, the combination with an engine, of a starting device therefor, including a dynamo electric machine having a set of motor armature windings of relatively low resistance and few turns, and an independent set of generator armature windings of higher resistance and a greater number of turns than the set of motor armature windings; motor field windings and generator field windings; a common magnetic mass common to the motor and the generator field windings and in proximity to which the said armature windings rotate; a storage battery; means connecting the electric machine with the engine; and selective means for connecting the storage battery with the motor armature windings and motor field windings for high torque cranking and for connecting the storage battery and the electric machine to the generator armature windings and generator field windings for charging purposes.

14. In an engine starting system, the

- combination with an engine; of a starting device therefor, including a dynamo electric machine having a motor armature winding and a generator armature winding; differential connecting devices including high and low ratio gearing between the engine and the starting device for starting the former by the latter and running the latter by the former; an accumulator; and an operating member movable from normal position to a position to connect the motor armature winding with the accumulator and to connect the electric machine with the engine through the high ratio gearing, and movable back to normal position to connect the generator armature winding with the accumulator, and establish the low ratio gearing connection.
15. An engine starting system comprising the combination with an engine, of a starting device therefor including a dynamo electric machine comprising a plurality of circuit connections including independent armature windings; an accumulator; connecting gearing including enmeshing members between the dynamo electric machine and the engine; and means for selectively connecting the accumulator with one of said circuit connections of the dynamo electric machine to effect an initial operation of said machine to facilitate the enmeshment of said connecting members, and to connect another circuit connection of said machine with the accumulator to effect a motor starting operation, and to connect said first circuit connection with the accumulator for charging said accumulator.
16. In an engine starting system in combination with an engine, a dynamo electric machine starting device including a plurality of armature windings; connections between said machine and said engine; an accumulator; and devices for selecting said armature windings of said machine and connecting the machine with the accumulator to produce first an initial movement resulting from low amperage current from the accumulator, second a cranking movement resulting from high amperage current from the accumulator, and third an accumulator charging period when said machine is driven by the engine.
17. An engine starting system comprising in combination with an engine, a starting device therefor including a dynamo electric machine having a pair of armature windings; means including enmeshing connecting members for connecting the starting de-
- vice with the engine; an accumulator; means for connecting said accumulator with one of said armature windings to operate the electric machine as a motor to facilitate the enmeshment of said connecting members; and means for connecting the accumulator with the other winding to cause the dynamo electric machine to crank the engine through said enmeshing members.
18. In an engine starting system, the combination with an engine, of a starting device therefor, including a dynamo electric machine having an armature winding of relatively low resistance and few turns and an armature winding of high resistance and a greater number of turns than the other winding; connections including enmeshing members between the engine and the starting device for starting the former by the latter and running the latter by the former; an accumulator; and means for connecting the accumulator with the armature winding of higher resistance and greater number of turns for facilitating the enmeshment of said connections, and for connecting the accumulator with the armature winding of relatively low resistance and few turns to cause the dynamo electric machine to operate as a high torque motor to crank the engine through said enmeshing members.
19. In an engine starting device for vehicles such as automobiles, the combination with a non-self-starting engine for propelling said vehicle; an accumulator; and a small electric motor provided with a plurality of armature windings, adapted for selective arrangements, with electrical connections from the battery for starting said engine; of means for connecting the engine and motor, including a toothed wheel connected with the engine shaft and a pinion adapted to be driven by the motor; and devices for selecting said armature winding arrangements to produce different armature conductivities, and contemporaneously controlling said pinion, said devices operating first to impart a combined movement of low torque registration and enmeshment to said pinion, and then to impart a high torque movement of rotation to said pinion when the proper enmeshment of said pinion is accomplished.
